Patented Oct. 21, 1958

183,770

ELECTRIC MOTOR

Werner W. Schwartz, Jackson Heights, N. Y., assignor to
Consolidated Sewing Machine Corp., New York, N. Y.,
a corporation of New York

Application October 26, 1956, Serial No. 43,544

Term of patent 7 years

(Cl. D26—5)

FIG. 1.

FIG. 2.

FIG. 3.

FIG. 4.

FIG. 5.

Fig. 1 is a top view of an electric motor embodying my new design.

Fig. 2 is a side view thereof.

Fig. 3 is an end view thereof.

Fig. 4 is a perspective view showing one end, one side, and the top of said electric motor.

Fig. 5 is a perspective view showing the opposite end, and opposite side, and also the top of said electric motor.

I claim:

The ornamental design for an electric motor, substantially as shown.
